4 Claims. (Cl. 179—138)

1

This invention relates to velocity (or pressure gradient) microphones.

The object of this invention is to avoid certain constructional features inherent in microphones of this type at present in use which render it impossible to use the magnetic field efficiently, and result in dimensions far greater than are ideally necessary.

Such microphones are usually of the ribbon type in which the diaphragm is an aluminum ribbon of the order of 2" long x 0.2" wide x 0.0002" thick clamped at each end and suspended in a transverse magnetic field.

The natural resonance frequency of this ribbon must be near the lowest audible frequency, i. e. 20 to 30 C. P. S. and, in order to achieve this, the stiffness of the suspension must be very low which means that the mean static position of the ribbon is not rigidly determined. In order that the ribbon shall move in uniform magnetic field whatever its stable position, the depth of the air-gap must be about 0.1" whereas the movement of the ribbon due to a sound field is not greater than .001".

According to the present invention, the ribbon of a velocity microphone is supported in such a manner that its static position in the air gap of the system is closely defined by supporting the ribbon along the full length of its edges instead of only at its ends, thus allowing the volume of the magnet system to be reduced without affecting the sensitivity or frequency characteristic of the microphones...

The invention will be fully understood from the following description of certain embodiments shown in the accompanying drawings in which—

Figure 1 is a plan view of the magnet system and ribbon of a microphone embodying the invention;

Figure 2 is a front elevation of the microphone shown in Figure 1;

Figure 3 shows a preferred form of ribbon for use in the microphone shown in Figures 1 and 2;

Figure 4 is a cross sectional plan view of a magnet system with a different form of dia-

phragm;

Figure 5 shows the magnet system and dia-

phragm of Figure 4 in elevation, while

Figure 6 is a view similar to Fig. 4 showing a modified form of the diaphragm of Figure 4.

The invention was first tried out experimentally with a flat gold leaf ribbon 4, Figures 1 and 2 about 5.10^{-6} inches thick which was mounted slackly between and attached to the pole-pieces 2, 3 carried by a semi-circular magnet 1. The rib-

bon was longer than the pole pieces and was also fixed at its end to which the electrical connections were made.

The tension across the ribbon varied from point to point along its length so that the natural resonance frequency of different sections of the ribbon were spread over a large frequency range; in consequence, there was no marked bass resonance. A fairly uniform response was obtained from 200 . . . 6000 C. P. S., the high bass cut off was due to the absence of corrugations in the ribbon.

If such a ribbon having a length ten times its width were provided with longitudinal corrugations along each edge having a radius one-tenth that used for lateral corrugations in the usual end-mounted ribbons, the thickness of the foil being of the order of one-hundredth of the usual thickness of ribbons, the bass cut off would be in the region of 50 C. P. S.

Since a ribbon microphone is a mass controlled device, there is for ribbons of identical dimensions a loss of about 20 db. in using gold instead of aluminium, the specific gravity of gold being 19.5 compared with 2.6 for aluminium.

This construction is capable of producing a microphone with a sensitivity of 90 db. below 1 volt/dyne/sq. cm., for a gold ribbon of 25 ohms resistance.

30 This method of construction is perhaps more of academic than practical interest, as such a thin ribbon may not be robust enough to stand the maltreatment which microphones usually receive.

35 If, however the ribbon 4 is made of a thermoplastic material such as cellulose acetate, or nylon of the order of 10^{-4} — 10^{-5} inches thick having a Young's modulus much lower even than aluminium or light alloy, longitudinally corrugated at the edges, and provided with an aluminium or light alloy armature 6 of Figure 3 of about the same thickness, the natural resonance of the diaphragm can easily be kept in the region of 50 C. P. S.

40 By slight adjustment of the spacing of the pole pieces after assembling the ribbon, the stiffness can be made progressively variable along the length of the ribbon and consequently the ribbon can be made to have different resonant frequencies along different sections of its length.

45 Due to the fact that the mean static position of the ribbon is closely defined the volume of the air gap can be reduced to about one-twentieth of that of the usual ribbon microphone enabling the volume of the magnet to be reduced in the

same ratio, the dimensions of the gap being, in a preferred embodiment, 0.156 inch wide x 0.0625 inch deep (pole-tip width).

The response at high frequencies can be improved by the use of cavity resonances on conventional lines.

The ribbon has three corrugations on each side of the aluminum armature, the corrugations having a lateral depth of about .005 inch with a radius of .010 inch. Figures 1 and 2 are twice full scale, while Figure 3 is twenty-five times full size.

The pole pieces are chamfered down to very narrow lateral dimensions, $\frac{1}{16}$ of an inch, at their tips, this being possible because the static position of the ribbon is closely defined. The ribbon was mounted on the side of the pole pieces in an experimental model, but it will normally be located symmetrically in the air gap, by dividing the pole pieces longitudinally and assembling the ribbon so that its edges are sandwiched between the divided pole-pieces.

As an alternative, the construction shown in Figures 4 and 5 may be employed. In these figures, which are four times full size, the central stiff area 10 of a thermo-plastic ribbon 4 has a cross-sectional form comprising two similar curved halves meeting at a central longitudinal apex on which is mounted a wire armature 6 of about .008 inch diameter. The ribbon is longitudinally corrugated on each side of the central stiff portion, the corrugations 5 having a preferred radius of .025 inch and overall depth of .020 inch.

The semi-circular magnet 1 carries flat pole pieces 2, 3 with apertures 9 designed to give the maximum possible air path to the diaphragm without increasing the reluctance of the magnetic circuit, and so that the diaphragm will respond to frequencies below 10,000 C. P. C. as if it were freely open to the air on both sides. The pole tips 7 are narrowed down to very small lateral dimensions, $\frac{1}{32}$ of an inch, and are very closely spaced to define a narrow air gap 8: about 0.18 inch wide, to receive the wire armature 6 of .008 inch diameter. The ribbon 4 is mounted along its longitudinal edges on spacers 13 about .015 inch thick on the pole pieces with the wire 6 positioned in the gap 8.

The wire armature 11, Figure 5 is connected by copper tapes 11 spot-welded or otherwise fixed thereto, to terminals 12.

Alternatively the two longitudinal corrugated halves 5a, 5b of the diaphragm on either side of electrode may be in different planes and facing in opposite directions as shown in Fig. 6, so that the two halves will be located on opposite sides of the plane of the magnet poles 2, 3 with the central stiff portion of the diaphragm at an angle thereto and passing through the air gap 8 and carrying the electrode 9 therein. This has the advantage that the resonant chambers 14, 15 which would be designed to resonate as near the upper limit of the frequency response range as possible, or above the frequency response range. In this way the response at the resonant frequency will be the same for sound waves approaching from both the front and from the back.

It may be advantageous to have the resonant chambers 14, 15 both on the same side of the

poles 2, 3 for some purposes, e. g. when the microphone is used in combination with a pressure microphone for matching purposes. In other circumstances, the arrangement shown in Fig. 6 will be advantageous.

What is claimed is:

1. A ribbon type velocity microphone comprising a structure of magnetic material having an air gap therein, a resilient ribbon having one longitudinal edge attached to the inside of said structure by a corrugated support and the other longitudinal edge attached to the outside of the structure by a similar support, said supports forming resonant cavities with the walls of said structure, said diaphragm passing through the air gap, and a linear conductor mounted on the ribbon within gap.

2. A ribbon type velocity microphone comprising a structure of magnetic material having an air gap therein, a resilient corrugated ribbon having one longitudinal edge attached to the inside of said structure by a corrugated support and the other longitudinal edge attached to the outside of the structure by a similar support, said supports forming resonant cavities with the walls of said structure, said diaphragm passing through the air gap, and a linear conductor mounted on the ribbon within the air gap.

3. A ribbon type velocity microphone comprising a structure of magnetic material having an air gap therein, a resilient diaphragm having a series of uneven longitudinal corrugations to vary the stiffness thereof having one longitudinal edge attached to the inside of said structure by a corrugated support and the other longitudinal edge attached to the outside of the said structure by a similar support, said supports forming resonant cavities with the walls of said structure; said diaphragm passing through the air gap, the transverse dimension of the corrugated resilient diaphragm having a progressive variation in the longitudinal direction with respect to the width of the air gap to give progressively different resonant periods along different sections of the diaphragm, and a linear conductor mounted longitudinally on said diaphragm within said air gap.

4. A ribbon type velocity microphone according to claim 3 wherein the said diaphragm comprises a thermoplastic material and wherein said linear conductor comprises a wire longitudinally mounted on said diaphragm and centrally positioned within the said magnetic gap.
